UNITED STATES PATENT OFFICE.

CLEON M. HANNAFORD, OF RICHMOND, VIRGINIA.

UNCOUPLING ATTACHMENT FOR CAR COUPLERS.

Application filed March 13, 1924. Serial No. 699,001.

To all whom it may concern:

Be it known that I, CLEON M. HANNAFORD, a citizen of the United States, residing at Richmond, in the county of Henrico and 5 State of Virginia, have invented a certain new and useful Improvement in Uncoupling Attachments for Car Couplers, of which the following is a full, clear, and exact description.

10 The object of this invention is to provide a simplified and efficient substitute for the links, chains, clevises, pins and cotters commonly used for connecting the operating mechanism fixed to the ends of railroad 15 cars with the uncoupling members forming parts of the car couplers.

The uncoupling attachment consists of a pair of flexibly connected unlike members, constructed and arranged as hereinafter explained, one of which members is adapted to be engaged with the lock-lift or the equivalent device of a car coupler, and the other of which is adapted to be connected with an operating mechanism fixed to the end of 25 the car and usually consisting of a rocking rod provided with an arm extending outwardly from the car and over towards the coupler, said attachment being so constructed as to permit of its removal without 30 taking down the operating mechanism, as I will proceed now to explain and finally claim.

In the accompanying drawings illustrating the invention, in the several figures of which 35 like parts are similarly designated, Figure 1 is a perspective view showing a part of the end of a car, the operating mechanism, and coupler, and the connecting device or uncoupling attachment of this invention. Fig. 40 2 is a perspective view of the connecting device detached; Fig. 3 is an elevation thereof, and Fig. 4 is a top plan view. Fig. 5 is an elevation, and Fig. 6 a top plan view showing a modification.

45 The invention is shown in Fig. 1 in connection with an approved type of automatic or Janney coupler, in which a lock-lift 1 is used to ensure the engagement of the couplers on adjacent cars and capable of 50 being raised to permit uncoupling of the cars, although the invention is applicable to other types of couplers, in which a coupling pin of some sort is used to control the operations of the couplers. This device 1 is 55 supplied with an eye 2 to be engaged by the

uncoupling attachment or connecting device. There is also shown an operating mechanism comprising a rod 3, part of which is shown mounted in bearings 4, one of which is shown, these bearings being 60 fixed to any suitable part of the end of the car. The rod 3 has an end extension or arm 5 projecting outwardly therefrom toward the coupler and having in its extreme end an eye or slot 6 to be engaged by the 65 connecting device.

As already stated, the connecting device is composed of two unlike members, the lower one of which designated 7 has a bottom portion or loop 8 of the general outline 70 of a U in side elevation, one limb of this loop terminating in an eye 9 arranged substantially at right angles thereto and the other limb 10 terminating short of the eye 9.

The other member of the connecting device, designated generally as 11, has an eye 12 at its upper end, with the free end 13 turned slightly aside and left open, and a shank 14, on the bottom of which is a transversely arranged block 15 having in its 80 opposite edges the grooves or notches 16 which straddle the limbs of the U-shaped portion of the lower member 7.

These two members, 7 and 11, are flexibly united, that is to say, they have freedom of 85 longitudinal movement and some lateral play, in order to compensate for the movements of the car, the coupler and the operating mechanism.

The connecting device is furnished to the 90 user with the limb 10 slightly open, as indicated by dotted lines in Fig. 3, to permit said limb to be engaged with the eye 2 of the lock-lift or other coupler control, and then this limb may be closed in as shown 95 in full lines in Figs. 1, 2, 3 and 4. The upper member 11 has its eye 12 engaged with the eye 5 in the arm 6 of the operating rod by a twisting movement. It is immaterial whether the connecting device is 100 applied to the operating rod or to the lock-lift first, although it is preferred to apply it to the operating rod because of the twisting motion necessary to effect such application.

105 Inasmuch as the shank 14 is of a length sufficient to drop the block 15 toward the bottom of the member 7, said block will rest on the top of the eye of the lock-lift and thereby the weight of the connecting de- 110

vice will serve to prevent accidental displacement or creeping or working out of the lock-lift in the operation of the car or coupler. It is not an infrequent occurrence in old style arrangements that the lock-lifts work up in the couplers and the cars thereby become uncoupled. This cannot occur with my attachment. The play of the upper member in the lower member of the attachment provides the necessary lost motion to prevent the accidental lifting of the lock-lift by the vibration of the operating rod and its arm. The necessary motion to effect the lifting of the lock-lift serves to bring the block 15 and the eye 9 into contact, after which the further movement of the operating rod serves to raise the connecting device and the lock-lift into unlocked and uncoupled position.

20 In case of damage to the car or coupler, and in any other case where it is necessary to disconnect the parts, the limb 10 may be opened and the connecting device detached from the lock-lift; or the eye 12 25 may be disconnected from the arm 6 by reverse twisting motion. In no case is it necessary to detach the operating rod wholly or in part from the car in order to effect the removal of the connecting device; 30 and yet the parts of the connecting device are so firmly connected to the lock lift and the operating rod that unauthorized removal is practically obviated or insured against.

In the modification shown in Figs. 5 and 35 6, the U-shaped or looped bottom member may be made a little wider than the corresponding member shown in Fig. 3, and the limb 17 may have its upper end terminating a distance sufficiently short of the eye 40 9 to admit the eye of the lock lift without spreading the limb 17 as is done in the case of limb 10. To further provide for the insertion of the eye of the lock-lift the block 18 may have its adjacent notch or 45 groove 19 enlarged, so that when the two members are pulled lengthwise this block may be tilted toward the right to permit the passage into the lower member of the eye of the lock-lift.

50 By the construction last described, it will be seen that a connecting device may be applied and also disconnected without bending its parts, although the manner of applying and removing may not be obvious 55 to the unskilled or to those who would attempt to surreptitiously disconnect the device. In any case, liability of disconnection in ordinary use is entirely removed.

By reason of the three-point guide, namely, the eye in the lower member and the notches or grooves in the block, the two members of the attachment are at all times in line and free to move with the coupler in all directions, without binding.

65 Variations in the details of construction

are considered to be within the principle and scope of the invention as herein explained and hereinafter claimed.

What I claim is:—

1. An uncoupling attachment for car 70 couplers, comprising two unlike members arranged one within the other in a flexible manner, one of the members of loop form having substantially parallel limbs and one of the limbs terminating in a transversely 75 arranged eye, and the other member having an open eye arranged outside of the first mentioned member and provided with a shank extending through the eye of the first mentioned member and terminating within the loop and having at such terminal a transversely arranged block provided with oppositely arranged 80 grooves which engage the limbs of the first mentioned member. 85

2. An uncoupling attachment for car 90 couplers, comprising two unlike members arranged one within the other in a flexible manner, one of the members being of loop form and having substantially parallel 95 limbs, one of said limbs terminating in a transversely arranged eye, and the other member having an open eye arranged outside of the first mentioned member and provided with a shank extending through the eye of the first mentioned member and terminating within the loop and having at such terminal a transversely arranged block provided with oppositely arranged 100 grooves which engage the limbs of the first mentioned member, the transverse eye and grooved block affording a three-point guide 105 for the movements of the members and serving to prevent binding, and said transverse eye serving as a stop to limit the outward movement of the block.

3. In an uncoupling mechanism for car 110 couplers having an operating mechanism and a coupler closing and opening control, an attachment for connecting the operating mechanism and the control, same comprising two unlike members, one of which has a substantially U-shaped part one limb of which terminates in a transverse eye and the other limb of which is open sufficiently to engage the control, the other member having an open eye adapted by a twisting motion to engage the operating mechanism, a shank passed through the transverse eye of the first mentioned member, and a transversely arranged block fixed on the end of the shank and having opposite notches in engagement with the limbs of the U-shaped member, the two members capable of flexing longitudinally 120 and transversely. 125

4. In an uncoupling mechanism for car 130 couplers having an operating mechanism and a coupler closing and opening control, an attachment for connecting the operating

mechanism and the control, same comprising two unlike members, one of which has a substantially U-shaped part one limb of which terminates in a transverse eye and the other limb of which is always open sufficiently to engage the control, the other member having an open eye adapted by a twisting motion to engage the operating mechanism, a shank passed through the transverse eye of the first mentioned member, and a transversely arranged block fixed on the end of the shank and having op-

posite notches of different depth in engagement with the limbs of the U-shaped member, the two members capable of flexing longitudinally and transversely. **15**

In testimony whereof I have hereunto set my hand this 8th day of March, A. D. 1924.

CLEON M. HANNAFORD.
